(57) **CLAIM**

The ornamental design for a cooler, as shown and described.

DESCRIPTION

FIG. 1 is a front, top, right perspective view of a cooler showing the new design;

FIG. 2 is a rear, top, left perspective view thereof;

FIG. 3 is a front elevation view thereof;

FIG. 4 is a rear elevation view thereof;

FIG. 5 is a right side elevation view thereof, the left side being a mirror image;

FIG. 6 is a top view thereof; and,

FIG. 7 is a front elevation view of the cooler in which the lids are in an opened position.
The broken lines in the drawings illustrate portions of the cooler which form no part of the claimed design.
